UNITED STATES PATENT OFFICE.

GEORGE ELISHA BUELL, OF ROCHESTER, NEW YORK.

ANATOMICAL BRACE FOR THE CURE OF FLAT FOOT.

No. 836,120.

Specification of Letters Patent.

Patented Oct. 9, 1906.

Application filed April 12, 1905. Serial No. 265,224.

To all whom it may concern:

Be it known that I, GEORGE ELISHA BUELL, of Rochester, county of Monroe, State of New York, have invented certain new and useful Improvements in Anatomical Braces for the Cure of Flat Foot, of which the following is a specification.

The object of my invention primarily is to produce a foot-brace or arch-support for a foot which, being designed and adapted to support the members of a foot in the form of the natural arch proper to it, without restraining the normal motion of the foot and without applying mechanical support save where it is indispensable is adapted to effect a permanent correction and cure of that deformity of the human body commonly known as "flat foot."

Inasmuch as the value of my brace depends for its efficiency as a curative agent upon perfect accuracy of fit to the foot whose deformity it is designed to correct; and where as the shapes and sizes of feet in the human species are of infinite variety, it is essential to provide practicable means of fitting the brace in each case in which it is to be used.

My invention therefore comprehends a brace fitted to the foot to be treated and comprising an unyielding portion and preferably means ancillary to the unyielding portion for applying and holding it in position upon the foot.

In the accompanying drawings, which constitute a part of this specification, Figure I is a side elevation of a human foot, showing the same in full lines with its normal arch and in dotted lines with its arch broken down into the shape commonly denominated "flat foot," the bony structure in each instance being indicated. Fig. II is a bottom plan view of the cast, illustrating also in dotted lines, as though produced by X-ray photography, the bony structure of the foot from which the cast is made, showing my brace fitted thereto with proper reference to the members of the foot and their joints and showing also a preferred mode of securing the brace to the foot within a flexible case. Fig. III is an inside view of the cast with a brace and its case fitted thereto. Fig. IV is a side elevation of the cast with its brace and case applied and fitted thereto, the view being from the opposite side to that shown in Fig. III. Fig. V is an inside perspective view of one of my braces and its case. Fig.

VI is a section taken as on the line VI VI of Fig. II.

The brace constituting my invention may be constructed in any suitable manner; but because it must conform accurately to the natural shape of the foot to be treated I prefer to construct it as follows: A plaster cast of the foot to be treated is made. Then the position of the foot's members and joints having been determined upon the cast the outline of the brace is drawn upon its bottom. With that drawing as guide the brace is cut and molded or fashioned into shape from a plate, as of sheet-brass, of suitable gage to render it practically unyielding to the weight of the body which it is designed to support.

In fitting the "brace" (by which term I designate exclusively the unyielding member, which is in its completed form, as hereinafter clearly specified, preferably incased in flexible material) its longitudinal extent is determined by a position at about the middle of the calcaneum (indicated by the numeral 8^a in Figs. I and II) and a point just behind the root of the great toe or the joint of the first metatarsal with its phalanx, the point being indicated by the reference-numeral 9 in Figs. I and II of the drawings. In transverse extent the brace, which is usually of a somewhat irregularly rhomboidal shape, as illustrated, for example, in Fig. II, having its corners rounded off, as indicated at 8^a, 9, 10, and 11, respectively, in that figure, and provided with a slightly reentrant side 12, extends under the tarsal and metatarsal bones underneath the foot (indicated by the reference-numeral 10) to the said bones. (Indicated by the reference-numeral 11 in Fig. II.) At the point 11 the arch of the brace is carried well up to impart to the foot its natural arch and to hold it in its normal position.

A brace constructed in accordance with my method above described and of the relative dimensions hereinbefore specified is adapted to perfectly support the arch of the foot, but without restraining any of its normal movements, the restraint of which would prohibit a permanent cure by interfering with the increase of muscular strength and the close knitting of the cartilaginous tissues upon which ultimate cure of the deformity sought to be remedied depends. This result is attained in a large measure by the use

of the reentrant side 12, which enables the brace to avoid interference with that part of the foot better left unsupported.

My brace is designed to be worn constantly while the wearer is afoot and is therefore preferably adapted for use inside of an ordinary boot or shoe.

It has been specified that restriction of the normal motions of the foot must not be prevented; but it is nevertheless necessary to hold the weak parts of the foot compactly together, as well as to provide an unyielding support for the arch of the foot. For that reason, as well as to hold the brace in place in use in an ordinary shoe I prefer to provide the brace 7 with a flexible covering, which may be made of two pieces of best sole-leather 15 and 16, (see Fig. VI,) glued or cemented together, with the brace 7 securely inclosed between them.

The longitudinal extent of the case composed as of the pieces 15 and 16, just specified, may extend longitudinally under the ball of the great toe-joint, as indicated by the reference-numeral 17 in Fig. II of the drawings, and toward the rear of the heel, as indicated by the reference-numeral 18 in said figure. If preferred, since it is perfectly flexible at those points, the case may be extended into a heel-pad 19 and a slightly laterally elongated toe-pad 20, as shown in Fig. V of the drawings.

In respect to the lateral extent of the case great care in fitting is necessary and less latitude in shape and dimensions is permissible. In respect to its lateral extent it is the function of the case to clasp the weak part of the foot and hold its members compactly together. The extent of the two parts of the case is well defined, and they are soaked in cold water to render them pliable and are molded upon the cast 6 so that when they are dry after being glued or cemented together and of preference stitched together

near their edges they retain their symmetrical shape and serve to hold the parts of the foot together in a compact mass. On the inner portion of the foot (see Fig. III) the case, which except in Fig. VI is for convenience designated by the reference-numeral 21, rises well above the scaphoid and all the prominent bones, to about one-half an inch below the malleolus covering and protecting the astragalo scaphoid junction. Upon the opposite or outside of the foot, (see Fig. IV,) the case covers the calcaneo cuboid junction and the outer aspect of the foot to a height sufficient to hold the foot securely and extends from the center of the heel to a point slightly behind the base of the fifth metatarsal.

What I claim is—

1. A brace for the cure of flat foot, which consists of an unyielding plate of triangular shape, arched to conform to the foot to be treated, the side of the triangular plate adjacent to the toes being slightly reentrant.

2. A device for the cure of flat foot, comprising an unyielding triangular brace-plate arched to conform to the natural shape of the foot and extending underneath the foot longitudinally from a point behind the first metatarsal phalanx junction to approximately the middle of the calcaneum and laterally from the fifth metatarsal cuboid junction to the other side of the foot, the side of the triangular plate adjacent to the toes being slightly reentrant, and a flexible covering for said plate adapted to hold the same in position upon the foot and to afford a yielding support therefor.

In testimony whereof I have hereunto signed my name in the presence of two subscribing witnesses.

GEORGE ELISHA BUELL.
